UNITED STATES PATENT OFFICE

HEINRICH BRUCKMANN, OF ESSEN, GERMANY

LAMP SHADE WITH A FABRIC COVER

Application filed May 16, 1931, Serial No. 537,876, and in Germany May 21, 1930.

The present invention relates to lamp shades provided with a fabric cover on supporting wires, pivots and the like, and has for its object to facilitate the difficult work 5 of attaching the cover and to simplify the supporting means for the fabric cover without spoiling the appearance and general aesthetic effect of the shade. In order to attain these objects, the invention provides supporting wires shaped and connected with the threads so that where the wires are inclined relative to both directions of the threads, i. e., diagonally to the threads, the fabric cover is subjected to tension either by the elasticity 10 of the fabric or supporting wires or by special means in such a way that the uneven surfaces lying between the supporting wires or pivots are brought into a saddle-shaped form.

In addition to the advantages indicated, the 20 invention affords the possibility of producing the cover as a whole separately from the supporting wire and of attaching it subsequently to the wires whereby the transportation of the shade is considerably facilitated.

25 By way of example, several embodiments of the invention are illustrated in the accompanying drawing, in which

Figure 1 is a diagrammatic view of the relative arrangement of the supporting wires 30 and threads;

Figs. 2 to 4 are detail views of a modification, in which the supporting wires are constructed essentially as annular rings of a cylinder or cone;

35 Figs. 5 and 6 are views of two different shades according to this modification;

Fig. 7 is a side view of a shade with helically extending supporting wires;

Figs. 8 and 9 show details of such a shade; 40 and

Figs. 10 and 11 are two views of a shade having a conical cover.

Referring to the drawing, in Fig. 1 a fabric 1 is shown, the threads 2, 3 of which extend 45 perpendicularly to one another. The fabric is practically inelastic in the direction of the threads while it may be tensioned in the two diagonal directions indicated by the arrows 4. When the fabric is placed on the two bent 50 supporting wires 5 and 6 and tensioned in the

direction of the arrows 4, a creaseless saddle-like surface will be produced between the supporting wires, which varies in depth according to the proportion and relative range of the two tensioning actions, proceeding perpendicularly to one another, and to the elasticity of the fabric. 55

In the modifications shown in Figs. 5 and 6 this effect has been made use of by constructing the supporting rings essentially as annular rings of a cylinder or cone, so that the threads of the fabric cone or cylinder attached to them extend in a line like the line 8 in Fig. 3, i. e. approximately in a helical fashion. To attain this condition, the strip 60 7 forming the fabric cover is preferably, according to Fig. 2, cut out obliquely of a piece of fabric at an angle of about 45° relative to the longitudinal direction of the fabric and the edges 8 are joined to form a seam (Fig. 3) 65 which extends helically in a cylindrical cover. 70

The supporting rings 9 (Fig. 5), which have a somewhat larger diameter than the untensioned fabric cover and over which the closed cover can be brought under tension, 75 may, in addition to being circular as shown, have a polygonal, angularly, curved or corrugated form and, as shown in Fig. 6, deviate from the plane of the circular area without causing the formation of creases. If a 80 plurality of such supporting wires 9 is employed, they may be displaced relative to one another, as Fig. 6 indicates, in order to provide for variations in form and to equalize uneven tension in the cover.

As the cover 85 is attached under tension and exerts pressure on the supporting rings, which acts concentrically on all sides, the rings will be kept automatically in form and position, and it is not necessary to connect the fabric 90 with them by sewing as is usual and, for this purpose, to wind band around them, which is quite bothersome. The action of the tensional pressure described makes it possible to employ very weak spring steel 95 wire as support in lieu of galvanized iron wire which has been used till now. In this modification, the supporting rings need not be interconnected, as the weight of the shade suffices to produce the necessary tensional 100

force in the direction of the cylinder-axis if the depth of the saddle-like surfaces is kept correspondingly small. The usual wire frame, which requires much time and labor to produce it, is replaced by thin wire rings which are independent of one another, while the added advantage is obtained that the entire lamp shade can be folded flat whereby packing and shipping are facilitated to a considerable extent.

If the saddle-like surfaces are to be made deeper, the difference between the diameters of the supporting rings 9 and the cover to be attached must be correspondingly greater and artificial tension in the direction of the axis of the shade provided for. As shown in Fig. 5, artificial tension may be imparted, for instance, by means of a plain or forked rod 10 spreading both ends of the shade.

The shade may be ornamented in the usual style with trimmings and cords arranged so as to conceal the seam 8 (Fig. 3). It is further possible to compose the cover 7 of several pieces of fabric in such a way that symmetrically extending seams 8 are produced, and it is not absolutely necessary to use the edges 8 (Fig. 2) for forming the seam.

The modification according to Fig. 5 indicates clearly the improved packing and shipping possibilities, as the relatively large shade can be folded to form a flat disc.

The main principle of the invention as explained in connection with Fig. 1 is embodied also in the modification shown in Fig. 7, in which the wires 11 bent in the manner of a single or multiplethread screw serve as supporting wires to which a cylindrical fabric cover 12 is attached, the threads of which extend in the direction of the cylinder generatrix or perpendicularly thereto. As the threads are everywhere inclined relative to the supporting wires, the effect produced is the same as described in connection with the preceding modification, that is, saddle-like channels having a pleasing effect are formed between the supporting wires and, in this case, extend helically.

The helical supporting wires 11 exert the requisite tensional pressure in both directions diagonally to the threads, which will produce saddle-like surfaces varying in form according to the proportion of the length and the diameter of the helix to the length and diameter of the cover. In order to fold such a shade, the ends of the helical supporting wires 11 are made of spring steel wire and, to be attached under pressure, can be inserted in corresponding holes or eyes of the closing rings 13 or in the small tubes 14 (Figs. 8, 9) arranged in the rings 13 which rings are preferably not circular in shape but have a form adapted to the cross section of the saddle-like surfaces.

In the helical arrangement (Fig. 7), the strips forming the fabric cover are cut out in

the direction of the threads, so that the seam 15 (Fig. 7) is directed vertically. The cover may consist also of several pieces of fabric so as to disclose several symmetrically distributed seams. To conceal the seam or seams, corresponding trimmings may be chosen or several of the helical tubes are combined into a single lamp body to render the seams invisible.

The application of the invention is not restricted to the hanging-lamp forms shown. The invention may equally well be used in connection with any other form of lamp, particularly pedestal lamps open on top or small standard lamps.

In the modifications shown in Figs. 10 and 11 the fabric cover is supported by a central pivot 16, such as, for example, the holder for the electric bulb, and by a circular ring 13. If a piece of fabric is placed over the annular ring 13 (Fig. 11) and subjected to uniform tension in all radial directions, it will expand more in the directions that are inclined relative to the threads than in the directions of the threads themselves, and show approximately the form indicated by the line 17 in Fig. 11. If the piece of fabric thus deformed be trimmed in accordance with the annular ring 13, it will have the form indicated by the line 18 when tension has completely ceased. Furthermore, if the fabric, without varying its line of limitation, be secured to a ring of somewhat smaller diameter than the ring 13 and loaded in the direction of the axis of the ring, a smooth, conical, slightly concave and creaseless surface of rotation (Fig. 10) will be produced.

This surface represents already a lamp shade of pleasing form, but may serve also as upper or lower closure for the shades shown in Figs. 5, 6 and 7, or two of these conical surfaces may be put together and combined into a shade. The tension to be exerted in the direction of the axis of the ring 13 (Fig. 10) is caused by the weight of the ring 13 or by other shade parts connected to it. There are no special tension rods or the like required to produce the necessary tension diagonally to the threads, and a shade according to this modification may also be folded flat for transportation.

If the shade is open below, as in Fig. 10, it is advisable to line its inside. For this purpose, the tubular fabric cover in the modification according to Fig. 5 is made correspondingly longer and turned back inside over the closing ring 13 (Figs. 8 and 9). In the modification shown in Fig. 11, two superposed pieces of fabric having the same size and being shaped along the line 18 are sewn together at their extreme lines of limitation whereupon the closing ring 13 adapted to be opened by a corresponding connection 19 (Fig. 4) is inserted through a suitable opening between the two pieces of fabric joined by sewing. In

both cases the inner cover will closely and ceaselessly hug the outer cover, provided the fabric has been tensioned in the manner indicated.

5 The invention may be embodied in other forms of lamps and wire arrangements than in the ones shown, and ceaseless saddle-like surfaces may be produced, for instance, by placing a square piece of fabric over two bent 10 wires forming a cross and securing the ends of the fabric under tension to the wires.

What is claimed, is:

1. In a lamp shade of the type described 15 a fabric cover comprising threads extending crosswise to one another, bent supporting wires holding the fabric in position and being inclined relative to the threads, and means adapted to subject the fabric to tension in the direction of the supporting wires 20 and also perpendicular thereto.

2. In a lamp shade of the type described 25 a fabric tube comprising threads extending crosswise to one another, supporting wires arranged in the tube and inclined relative to the threads of the tube, and means for 30 subjecting the fabric to tension in the direction of the supporting wires and also perpendicularly thereto.

3. In a lamp shade of the type described 35 a fabric cover comprising an oblique strip cut out from a piece of fabric and sewn together at its edges to form a tube, circular supporting rings having a diameter slightly in excess of that of the fabric tube and being arranged in the tube, and means adapted 40 to subject the fabric to tension in the direction of the axis of the tube.

4. In a lamp shade of the type described 45 a fabric comprising threads extending crosswise to one another, supporting wires inclined relative to the threads and made of thin spring steel wire, the said supporting wires being kept in their form and position by concentrically acting tensional force of the fabric.

5. In a lamp shade of the type described 50 a fabric cover comprising threads extending crosswise to one another, bent supporting wires holding the fabric and inclined relative to the threads, means adapted to subject the fabric to tension in the direction of the supporting wires and also perpendicularly thereto, and a second fabric cover equally tensioned and equal to the first one in form 55 and size and covering the inner surface of the first cover.

6. In a lamp shade of the type described 60 a fabric tube comprising threads extending crosswise to one another, supporting wires arranged in the tube and inclined relative to the threads of the tube, means for subjecting the fabric to tension in the direction of the supporting wires and also perpendicularly thereto, and an end ring over which 65 the fabric tube is turned back inside, the

inner portion being tensioned in the same manner as the outer one.

7. In a lamp shade of the type described 70 a fabric tube comprising threads extending crosswise to one another, supporting wires arranged in the tube and inclined relative to the threads of the tube, and an end ring tensioning the fabric in the direction of the axis of the tube by its own weight.

8. In a lamp shade of the type described 75 a piece of fabric with threads extending crosswise to one another, a pivot holding the piece of fabric in the center, an annular supporting wire holding the piece of fabric at its extreme lines of limitation, the said piece 80 of fabric being in untensioned condition differentially shortened in the radial directions disposed diagonally to the threads, and means for exerting tension on the fabric between the pivot and supporting wire in a 85 direction extending vertically to the plane of the supporting wire.

The foregoing specification signed at Cologne, Germany, this 8th day of May, 1931.
